UNITED STATES PATENT OFFICE.

CHARLES F. LEEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

SPRING-GUN.

1,097,244.

Specification of Letters Patent. Patented May 19, 1914.

Application filed May 31, 1913. Serial No. 771,013.

To all whom it may concern:

Be it known that I, CHARLES F. LEEFEVER, a citizen of the United States of America, residing at Plymouth, in the county of Wayne and State of Michigan, have invented certain new and useful Improvements in Spring-Guns, of which the following is a specification, reference being had therein to the accompanying drawings.

10 The invention relates to guns of that type in which the power for propelling the projectile is first stored by a manual operation, and the present invention comprises the peculiar construction of means employed for 15 storing the power as hereinafter set forth.

In the manufacture of toy guns, it is desirable to simulate as closely as possible both the appearance and the manipulation of a firing gun. Thus the compression of 20 the spring which stores the power is in some cases effected by breaking down of the gun at the bridge similar to the operation of the firing guns of this type, and it has also been proposed to effect the storing of the power 25 by a slidable handle block similar to the so-called pump guns. There is, however, a difficulty to be overcome in the latter type, as the power required to fully compress the spring is such as to render the sliding of 30 the handle block difficult and often beyond the strength of the juvenile operator. The present invention is designed to overcome this difficulty by the interposition of mechanism for progressively increasing the 35 power directly applied to the spring as the latter increases in tension. This renders it possible to simulate the construction and operation of the pump gun and at the same time to have an easily operated mechanism.

40 In the drawings: Figure 1 is an elevation of the gun; Fig. 2 is a longitudinal section through a portion of the gun showing the power storing mechanism; Fig. 3 is a similar view showing the parts in different positions of adjustment; and Fig. 4 is a cross section.

A is the barrel of the gun, B the stock, C the trigger and D the handle slidable longitudinally of the barrel, and, as specifically 45 shown, directly mounted thereon.

E is the spring to be compressed, the rear end of which engages an abutment F while the forward end bears against the piston or plunger having a rearwardly-extending 55 shank G for engagement with the trigger

and power-storing mechanism. To compress the spring, the power required increases as the limit of compression is reached, and while the initial movement is easily performed the final movement is 60 much more difficult. I therefore interpose between the slidable block D and the shank G a lever mechanism so constructed that the power applied to the shank increases as the spring approaches its final position of compression. This mechanism preferably comprises a toggle lever, which in its initial position has its constituent links H and I in acute angular relation to each other, while in the final position these links are 65 straightened approximately into alinement. The link H in initial position extends transversely of the barrel, substantially at right angles to the axis thereof, and is provided with a bent arm J extending parallel to the 70 under side of the barrel. This arm J is pivoted at its free end to a link K which extends to the block D and is pivotally attached thereto, the pivot K' between said links being slightly out of alinement with 75 the pivots K² and J' respectively connecting the link K to the block D and the links H and I of the toggle. Thus a longitudinal movement of the block D along the barrel will cause the links J and K to break down 80 or fall upon the pivot K' and will also swing the link H from its initial to its final position, as shown in Fig. 3. In the straightening of the toggle links H and I by the movement just described the shank 85 G is guided within the barrel by a portion G' which slidably bears upon the top of the barrel, and the link I is provided with a pin I' which engages a bifurcated hooked bearing L on the lower side of said shank. 90 In rear of this bearing is the hook L' which engages with the sear C' of the trigger C. Thus when the toggle links H and I are straightened by the movement as above described, the hook L' will engage with the 95 sear C' so as to hold the shank G from return movement, but the block D and levers connected therewith are free to be returned owing to the detachable engagement of the pin I' with the bifurcated bearing L on the 100 shank G. To hold these parts in their return position prior to the firing of the gun, a latch member M is arranged to yieldably engage with the pin I'. This member M is 105 preferably bifurcated to embrace the links 110

- H and I and is pivotally mounted upon the pin N which forms the pivot for the trigger. The free ends of the furcations are formed with shoulders M' for engaging with the pin I', being yieldably pressed into engagement by a spring O bearing against the member M and the stock B. The spring O' arranged adjacent to the spring O bears against the trigger.
- 10 With the construction as described, in operation, the spring is compressed to store the power by drawing rearward upon the slideable block or handle D, which moves the parts from the position in Fig. 2 to that shown in Fig. 3. During this operation the toggle levers which actuate the shank G are first arranged for relatively large movement and small power but constantly change toward increasing power and decreasing movement in direct ratio to the increasing resistance of the spring as it is compressed. Thus the power is stored quickly and easily by the operator and without the necessity of removing the gun from a position of aim.
- 15 The return movement of the block D permits the latch member M to engage with the pin I', which will prevent said block from sliding down where the gun is aimed upward. During this return movement the pin I' is guided between the shank G and the furcations of the member M until it engages with the shoulder M'. The pulling of the trigger releases the sear, permitting the spring to expand and return the shank G to a position where the pin I' again engages the bearing L, while the hook L' forces the latch member M out of engagement with the pin I'. A cap member P is preferably employed for covering the toggle links and the opening in the gun barrel through which they operate. This cap member is pivoted at P' and extends over the bent arm J of the link H, while the spring P² operates to hold it in normal position. The tension of this spring is slight, so as not to interfere with the movement which compresses the main spring, but it nevertheless assists in returning the levers after the storage of the power.
- 20 What I claim as my invention is:
1. In a gun, the combination with a barrel of power storage means for propelling the projectile, an actuating member movable by a sliding movement longitudinally of the barrel, and a transmission between said actuating member and power storage means for progressively increasing the power applied to the latter as the resistance thereof increases.
2. In a gun, the combination with a barrel of power storage means for propelling the projectile, an actuating member slideable longitudinally of the barrel, and a lever connection between said actuating member and said power storage means constructed to in-

crease the power exerted upon the latter as its resistance increases.

3. In a gun, the combination with a barrel of power storage means, an actuating member slideable longitudinally of the barrel, and a toggle lever connection between said actuating member and said power storage means constructed to impart to the latter decreasing movement and increasing power.

4. In a gun, the combination with a barrel of a power storage spring arranged longitudinally thereof, an actuating member slideable longitudinally of the barrel, and a lever connection between said actuating member and said power storage spring including toggle links initially in acute angular relation to each other and approaching a position of alinement during their final movement.

5. In a gun, the combination with a barrel of a power storage spring arranged longitudinally thereof, a shank for compressing said spring, an actuating member slideable longitudinally of the barrel, toggle links for retracting said shank, initially in acute angular relation and approaching during their movement a position of alinement, and a break-down lever connection between said links and said slideable actuating member.

6. In a gun, the combination with a barrel of a power storage spring arranged therein, an actuating member slideable longitudinally of the barrel, a shank for retracting said spring, toggle links for actuating said shank, initially in acute angular relation and approaching alinement in their final position, an extension arm of one of said links initially arranged parallel to the barrel, and a link pivotally connected to said extension arm and to said slideable actuating member.

7. In a gun, the combination with a barrel of a power storage spring therein, a shank for compressing said spring extending rearward therefrom, toggle links interposed between said spring and said shank, initially in acute angular relation, an arm forming an extension of one of said links initially arranged parallel to said barrel, an actuating member slideable longitudinally of the barrel, and a link pivotally attached to said actuating member and to said extension arm for moving the latter to straighten said toggles and compress said spring.

8. In a gun, the combination with a barrel of a power storage spring arranged therein, a shank for compressing said spring extending rearward therefrom, toggle links interposed between said spring and shank, initially in acute angular relation, one of said links extending in its initial position transversely of said barrel and being provided with a forwardly-extending arm parallel to said barrel, an actuating member slideable

longitudinally of said barrel, and a link pivotally connected to said actuating member and to the forwardly-extending arm of the toggle link for the purpose described.

5. 9. In a gun, the combination with a barrel of a power storage spring therein, a bifurcated shank for compressing said spring extending rearward centrally thereof, toggle links arranged intermediate said spring and shank initially in acute angular relation, one of said links comprising a portion extending transversely of said barrel intermediate the furcations of said shank and a portion extending forward parallel to said barrel, the other link being pivotally attached to the lower end of said transversely extending portion and provided at its free end with a pin for engaging a bearing on said shank, an actuating member slidable 15 longitudinally of said barrel, a link pivotally connected to said actuating member and to said forwardly-extending arm, and a latch member for engaging said pin after the power-storing operation to hold said actuating member and connections from displacement.

10. In a gun, the combination with a barrel of a power storage spring therein, a rearwardly-extending shank for compressing said spring, toggle links for actuating said shank, an actuating member slidable longi-

tudinally of said barrel, a connecting linkage between said actuating member and said toggle links, a sear for retaining said shank in the compressed position of said spring, 35 and means for holding said actuating member from displacement in its initial position after the power-storage operation.

11. In a gun, the combination with a barrel, of a power storage spring therein, a shank for compressing said spring extending rearwardly therefrom, toggle links intermediate said spring and shank initially in acute angular relation, one of said links being provided with a forwardly-extending 40 arm parallel to said barrel, an actuating member slidable longitudinally of said barrel, a link pivotally connecting said actuating member with said forwardly-extending arm, a pin at the free end of said toggle 45 links for engaging said shank, and a member engaging said pin for guiding the same during its return movement after the power-storage operation, and for holding the same and said actuating member from displacement from their initial positions.

In testimony whereof I affix my signature in presence of two witnesses.
